UNITED STATES PATENT OFFICE.

JOSEPH H. COLEMAN, OF TOTTENHAM, ONTARIO, CANADA.

FARE-COLLECTING APPARATUS.

No. 913,698.

Specification of Letters Patent.

Patented March 2, 1909.

Application filed June 4, 1908. Serial No. 436,701.

To all whom it may concern:

Be it known that I, JOSEPH H. COLEMAN, of the town of Tottenham, in the Province of Ontario, Canada, have invented certain 5 new and useful Improvements in Fare-Collectors, of which the following is a specification.

My object is to devise means for conveniently collecting fares, as a passenger enters 10 a car without requiring the use of a portable fare box. In devising such apparatus several requirements must be kept in view. First—it must be so constructed as to make it impossible for the passenger to pass off 15 a worthless or imitation fare undetected; second—it must be so constructed as to make it impossible for the passenger to deposit his fare in the apparatus in such a way that the conductor can remove it and appropriate it; 20 third—the abstraction of individual fares after they have passed into the apparatus must be prevented; fourth—means must be provided whereby the boxes in which the fares are collected cannot be removed from the apparatus in an unlocked condition. 25

Broadly speaking my apparatus comprises a fare receiving receptacle having a bottom which may be operated to "turn down" the fare, a chute into which the fare is "turned 30 down," a box in which the fares are collected as received from the chute and means for opening the box as it is inserted into the apparatus and for locking it before removal.

My present invention relates particularly 35 to improvements in the means for locking the fare box, and to improvements in certain other details of the apparatus as hereinafter more specifically described and then definitely claimed.

40 Figure 1 is a perspective view of my improved fare collector. Fig. 2 is a side elevation of the same partly in section. Fig. 3 is an end view of the same with the casing partly broken away. Fig. 4 is a plan view 45 of the drawer with the fare box drawn out. Fig. 5 is a side elevation partly in section of the fare box and drawer partly drawn out. Fig. 6 is a plan view of the rocking bottom of the fare receptacle in its normal position. 50 Fig. 7 is a similar view showing the bottom rocked to "turn down" a fare. Fig. 8 is an end elevation showing the rocking bottom of the swinging gate which normally closes the opening through which the fares are 55 "turned down". Fig. 9 is a side elevation

showing the arm which limits the movements of the rocking bottom. Fig. 10 is a cross section of one of the sides of the hopper of the fare receptacle.

In the drawings like numerals of reference 60 indicate corresponding parts in the different figures.

The device is intended for use as described in my prior patent No. 875,781 and is located beside the entry to the car. The 65 parts are all contained within the casing 1, of suitable shape and having its top formed as a table or counter on which the conductor may mark his transfers, make change and conduct his other business with the passengers entering the car. At the top of the casing is located a fare collecting receptacle 2. This fare receptacle comprises four glass walls 3, suitably held in a metal frame. The bottom of the receptacle is closed by a rocking bottom 4, intended to retain the fares until the latter are properly "turned down" by the conductor. This rocking bottom comprises a segment of a cylinder closely fitted to the bottom of the frame of the receptacle 80 2. A flat is formed at one part of the surface of this segment which normally forms a flat bottom for the receptacle as shown in Fig. 2. The curved outer surfaces of the rocking bottom are provided with circumferential ribs 5. The bottom of the outer wall of the receptacle formed by part of the frame supporting the glass plates is suitably notched to fit these ribs. (See particularly 85 Figs. 2, 6 and 7). The purpose of this construction is to prevent tickets or cash fares becoming jammed between the surface of the rocking bottom and the outer wall of the receptacle.

An opening 6 is formed between the bottom of the opposite wall of the fare receptacle and the rocking bottom and through this opening the fares are "turned down", when the bottom is rotated to the position shown in Fig. 7. This opening is normally 100 closed by the swinging gate 7 suitably hinged at its upper edge (see particularly Figs. 2 and 8). The opening 6 prevents any jamming of fares when a number are "turned down" together and at the same time, the 105 gate prevents any individual fares from falling through until regularly "turned down" by the conductor.

The lower edge of the gate is preferably 110 notched to fit the rib 5 of the rocking bot-

tom. The rocking bottom is operated by means of a hand lever 8 suitably pivoted on the frame of the apparatus and extending to a point convenient to the conductor's hand. 5 To its lower end is pivotally connected the link 9, the other end of which is connected to the arm 10 connected to the rock shaft 11 to which the rocking bottom is secured. This shaft is journaled in suitable brackets 10 12, formed on or secured to the frame of the machine (see Figs. 2, 3, 8 and 9). To limit the movement of the rocking bottom in either direction I secure to the shaft 11 an arm 51 and secure to the plane at either side 15 thereof the stops 52 with which the end of the arm may engage. I also secure to the lever 8 a coil spring 38, the other end of which is secured to the frame. This spring tends to retain the parts in their normal 20 position.

For the purpose of preventing the illicit abstraction of fares from the fare receptacle, I have adopted the construction I will now describe.

25 A hopper is formed at the upper part of the fare receptacle by means of the transparent plates 13, which have an opening between their lower ends preferably constructed to one side as shown in Fig. 2. 30 Below the upper plates are secured the oppositely inclined baffle plates 14 which are also transparent. The opening between the lower ends of these plates is preferably out of alinement with the opening between the 35 lower ends of the hopper plates and to the opposite side of the center of the plane to that towards which the opening between the lower ends of the upper plates faces. The purpose of this is two fold. It is thereby 40 rendered impossible to introduce any tool through to the bottom of the receptacle to abstract coins and any fares are directed towards the outer side of the rocking bottom where they are readily seen by the conductor and in such a position that if the conductor happens to have partly turned the rocking bottom to "turn down" a fare, the last introduced fare will not slide through the opening 6 without being seen 45 but will fall onto the ribbed portion of the bottom which now begins to appear at the bottom of the receptacle.

Much difficulty was experienced with the fare receptacle as it was constructed. The 50 walls of the hopper at the upper part of the receptacle being of plain glass, coins were wetted and would then stick to the walls of the hopper when passed on and were subsequently appropriated by the conductor. 55 Much difficulty was experienced in overcoming this trouble, but it was finally accomplished by the following construction:—Instead of forming the side walls of the hopper with continuous plane surfaces, they 60 were formed with discontinuous surfaces,

preferably by forming them with a series of downwardly directed ribs 15. (See particularly Figs. 1, 2 and 10). This ribbing by preventing any large or continuous plane of contact between the coin and the walls of the hopper effectually overcame this method of illegally appropriating fares.

I do not desire to limit myself, of course, to the specified method of forming the discontinuous surfaces shown in the drawings 75 as many variations may be devised which would fall within the scope of my invention.

Further trouble was experienced through parties desirous of cheating the apparatus for the benefit of the conductor depositing 80 wetted coins on the edges of the rim of the hopper or on the angle where the two sides meet. It was found necessary therefore to bevel the edges of the rim 53 of the hopper almost to a knife edge so that no coin could 85 be balanced thereon as a passenger passed the apparatus. Even though the edges were beveled to a knife edge, it was still possible to rest a coin on the angles between them and I have therefore provided each angle with an 90 upward projection 54 beveled or tapered to a rounded point on which no coin can rest. The combination of these two features, the beveled edges of the rim and the upward 95 projections at the corners has resulted in a complete defeat of such attempts to beat the apparatus.

The fares are "turned down" into the fare chute 16 in the upper end of which the rocking bottom is located. This chute is intended 100 to discharge into the fare box 17 (see Fig. 2). A hinged gate 50 is hung at one side of the chute near the bottom and is of such a length that if the whole apparatus be turned upside down, it will swing back and 105 close the chute to prevent any fares returning from the fare box through the chute. The fare box is carried by a drawer 18 from which it is removable when the drawer is in the position shown—in Fig. 4. This drawer 110 comprises an open metal frame work 19 secured to two round guide rods 20 which slide in guides 21 on the frame of the apparatus. The drawer can thus be pushed into the position shown in Fig. 2, or pulled into 115 the position shown in Fig. 4. In the front of the apparatus is formed an opening 22 for the drawer and the front—23—of the drawer forms a closure for this opening.

Each fare box 17 is provided with a 120 hinged cover 24, provided with a spring lock 25 of any suitable construction. The opening 22 (which will be seen particularly on reference to Fig. 5) is of suitable height to admit the box with the lid in the position 125 shown with the spring lock disengaged. Means must be provided however to raise the lid to the wide open position in order that the opening in the box may be made to register with the opening in the chute 16 as 130.

shown in Fig. 2. For this purpose I provide within the casing one or more hinged hooks 26 which are adapted to engage the free edge of the cover and raise it to the vertical as the box is pushed into position. The hooks are preferably provided with two notches 27 to insure that there shall be a proper engagement between the hooks and the cover, the position of the latter being sometimes liable to slight variations when the latter is in the position shown in Fig. 5. The heel of each of the hooks 26 is provided with a seat 28 which is adapted to engage a cross bar of the frame as shown in Fig. 5 to prevent the arm 15 dropping too low. It has sometimes been found that boxes may accidentally be snapped shut before they are placed in the apparatus. To avoid this I pivot a small dog 29 on the side of each fare box, its upper end engaging beneath a lip 30 formed at the side of the cover 24 near its free edge. The lower end of the dog lies in the path of the longitudinal bar 31 secured to the frame of the machine. As soon as the lower end of the 25 dog engages this bar as the drawer 18 is pushed into place, the dog will be rocked to the position shown in Fig. 2 and when in this position it forms no obstacle to the closing of the cover as hereinbefore described.

30 The method of closing the cover before the box is withdrawn is an important feature of my device. In my prior patent No. 875,781 this closing of the cover was accomplished directly through the agency of the box the cover of which engaged a rocking arm which, as it swung into the vertical position, forced down the box lid. I now accomplish the same result independently of the box by mechanism operated by the sliding movement of the drawer containing the fare box. The closing is effected through the agency of the rod 32 vertically movable in the guides 33, on the frame of the apparatus. The lower end of the rod is preferably provided with a friction roller 34 (see Figs. 2 and 5). A cross shaft 35 is secured to this vertical rod and this cross shaft has its ends journaled in levers 36 fulcrumed on brackets 37, one on each side of the machine. 40 The rear or inner ends of these levers 36 are provided with projections preferably in the form of friction rollers 39. It is evident that by moving these projections vertically the levers will be operated to raise or lower the rod 32. For the purpose of rocking these levers I support from the frame work 19 and guide rods 20 of the drawer 18 a pair of tracks or ribs 40, which may pass above or below the projections. To cause these 45 ribs to pass alternately above and below the projections as the drawer is reciprocated, I provide each rib with an inclined plane or switch point 41, pivoted on the rib at 42 and normally held in the position shown in Figs. 2 and 5 by a coil spring 43. A second

rib 44 is preferably formed below each of the ribs 40 to prevent the projections 39 dropping too low and also to limit the downward movement of the inclined planes 41. A coiled spring 45 is also preferably placed on the rod 32 between the lower guide 33 and the cross shaft 35 which tends to raise the rod 32.

50 The operation of the cover closing device is as follows:—When the parts are in the position shown in Fig. 2 the drawer is drawn out by means of the handle 46. The inclined planes 41 gradually rock the levers 36 by lifting the projections 39 and the rod 32 is caused to press on and close the cover. While the downward movement of the rod 32 may be sufficient to snap down the cover I prefer to form an inclined plane 47 on the cover which aids the process by gradually pressing down the cover as the box is drawn beneath the roller of the rod 32. Before the drawer has been drawn out to the position shown in Fig. 4 the cover is automatically locked and as soon as the drawer is completely drawn out, the closed and locked fare box may be removed. It will be noted that the front—23—of the drawer is provided with an extension 48 which when the drawer is pushed home extends inwardly some distance from the opening 22. The purpose of this extension is to maintain the closure of the opening 22 until such time as the projections have ridden well up on the inclined plane 41 so that it is impossible to insert tools through the opening 22 to lift the inclined planes 41 to permit the projections to pass underneath the same as the drawer is pulled out and thus prevent the operation of the closing means to close the cover of the box before its withdrawal. It will be noted that the ribs 40 are of such a length that as soon as the cover is closed they have passed through underneath the projections and the inner ends of the levers 36 drop to allow the projections to rest on the lower ribs 44. The closing rod 32 is now raised and offers no bar to the introduction of a fare box and the raising of this lid as the drawer is pushed home. As the drawer is pushed in after the levers have dropped as aforesaid the projections resting on the ribs 44 lift the inclined planes 41 and pass under them, the latter resuming their original position immediately the projections have passed, ready to operate the closing means the next time the drawer is withdrawn.

55 With the arrangement just described it will be found impossible to withdraw the fare box until the cover has been snapped to and securely locked. The outer casing 1 is provided with a hinged door 49 closing the opening 22 through which the drawer is withdrawn. A suitable lock is provided for this door.

The procedure with regard to the insertion and removal of the fare box will be substantially as follows:—A special official will bring the box to the car, place it in the 5 drawer, push the drawer into position and lock the door of the casing. At the close of the day the official will remove the fare box, locking each through the action of the drawer as it is withdrawn. At the same 10 time an empty box will be placed in position ready for the next trip.

While I have described the apparatus in its entirety, the fare receptacle with its rocking bottom is made the subject matter of my 15 co-pending application, Ser. No. 445,277.

What I claim as my invention is:—

1. In fare collecting apparatus the combination of a chute for fares; a removable box below the lower end of the chute; a 20 cover for the box; means within the apparatus adapted to close the cover; and means independent of the box and operable from without the apparatus for moving the closing means towards the closing position.

2. In fare collecting apparatus the combination of a chute for fares; a removable box below the lower end of the chute; a cover for the box; a lever pivoted within the apparatus and adapted to close the cover; 30 and means independent of the box and operable from without the apparatus for rocking said lever.

3. In fare collecting apparatus the combination of a chute for fares; a removable box below the lower end of the chute; a cover for the box; a sliding bar adapted to engage the cover to close it; a lever pivoted within the apparatus and pivotally connected to said bar; and means independent 40 of the box and operable from without for rocking said lever.

4. In fare collecting apparatus the combination of a casing having an opening therein for the introduction of a fare box; a chute for fares; a box for fares below the lower end of the chute and removable through the aforesaid opening; a cover for the box; means within the apparatus for closing the cover movable to and from the 50 closing position and normally retracted; a closure for the aforesaid opening; and means whereby the act of opening the closure moves the closing means to the operative position.

5. In fare collecting apparatus the combination of a casing having an opening therein for the introduction of a fare box, a chute for fares; a drawer slid able through said opening to a position below the chute the front of the drawer forming a closure for the opening; a fare box removably carried by said drawer; a cover for the box; means within the apparatus for closing the cover movable to and from the closing position;

and means operable by the drawer for moving said closing means.

6. In fare collecting apparatus the combination of a casing having an opening therein for the introduction of a fare box; a chute for fares; a drawer slid able through said opening to a position below the chute, the front of the drawer forming a closure for the opening; a fare box removably carried by said drawer; a cover for the box; means within the apparatus for closing the cover movable to and from the closing position; a pivoted inclined plane carried by the drawer adapted on the outward movement of the drawer to engage the closing means to move them towards the closing position and to pass by out of engagement, its pivoted support permitting of its return movement as the drawer is closed without affecting the closing means.

7. In fare collecting apparatus the combination of a casing having an opening therein for the introduction of a fare box; a chute for fares, a drawer slid able through said opening to a position below the chute the front of the drawer forming a closure for the opening; a fare box removably carried by said drawer; a cover for the box; means within the apparatus for closing the cover movable to and from the closing position; a projection on said means whereby it may be operated; a rib carried by said drawer adapted to slide either at one side or the other of said projection as the drawer is reciprocated; and a pivoted inclined plane or switch point at the forward end of said rib normally yieldingly held in position to move the projection to cause the lid closing means to assume the closing position as the drawer is drawn outward, the rib being so proportioned that when the drawer is fully drawn out the projection is free to pass to the other side of the rib and to lift and pass the switch point as the drawer is pushed in again.

8. In a fare collecting apparatus the combination of a casing having an opening therein for the introduction of a fare box; a chute for fares; a drawer slid able through said opening to a position below the chute the front of the drawer forming a closure for the opening; a fare box removably carried by said drawer; a cover for the box; means within the apparatus for closing the cover movable to and from the closing position; means operable by the drawer for moving said closing means; and a rearward extension of the front of the drawer adjacent to the closing means adapted to maintain the closure of the opening in the casing until said means have been moved towards the closing position.

9. In fare collecting apparatus the combination of a casing having an opening therein

for the introduction of a fare box; a chute for fares; a drawer slideable through said opening to a position below the chute the front of the drawer forming a closure for the opening; a fare box removably carried by said drawer; a cover for the box; means within the apparatus for closing the cover movable to and from the closing position; a pivoted inclined plane carried by the drawer adapted on the outward movement of the drawer to engage the closing means to move them towards the closing position and to pass by out of engagement, its pivoted support permitting of its return movement as the drawer is closed without affecting the closing means; and a rearward extension of the front of the drawer adjacent to the closing means adapted to maintain the closure of the opening in the casing until said means have been moved towards the closing position.

10. In fare collecting apparatus the combination of a casing having an opening therein for the introduction of a fare box; a chute for fares; a drawer slideable through said opening to a position below the chute the front of the drawer forming a closure for the opening; a fare box removably carried by said drawer; a cover for the box; means within the apparatus for closing the cover movable to and from the closing position; a projection on said means whereby it may be operated; a rib carried by said drawer adapted to slide either at one side or the other of the projection as the drawer is reciprocated; a pivoted inclined plane or switch point at the forward end of said rib normally yieldingly held in position to move the projection to cause the lid closing means to assume the closing position as the drawer is drawn outward, the rib being so proportioned that when the drawer is fully drawn out the projection is free to pass to the other side of the rib and to lift and pass the switch point as the drawer is pushed in again; and a rearward extension of the front of the drawer adjacent to the closing means adapted to maintain the closure of the opening in the casing until said means have been moved towards the closing position.

11. In fare collecting apparatus the combination of a casing having an opening therein for the introduction of a fare box; a chute for fares; a drawer slideable through said opening to a position below the chute the front of the drawer forming a closure for the opening; a fare box removably carried by said drawer; a cover for the box; a vertical movable rod adapted to engage the fare box cover to close it; a rearwardly extending lever suitably fulcrumed and connected to said rod; a projection on said lever whereby it may be operated; a rib

carried by said drawer and adapted to slide either above or below said projection as the drawer is reciprocated; and a pivoted inclined plane or switch point at the forward end of said rib normally yieldingly held in position to move the projection to cause the lever to move the aforesaid rod to a position to engage the fare box cover as the drawer is drawn outward, the rib being so proportioned that when the drawer is fully drawn out the projection is free to pass to the other side of the rib and to lift and pass the switch point as the drawer is pushed in again.

12. In fare collecting apparatus the combination of a casing having an opening therein for the introduction of a fare box; a chute for fares; a drawer slideable through said opening to a position below the chute the front of the drawer forming a closure for the opening; a fare box removably carried by said drawer; a cover for the box; a vertical movable rod adapted to engage the fare box cover to close it; a rearwardly extending lever suitably fulcrumed and connected to said rod; a projection on said lever whereby it may be operated; a rib carried by said drawer and adapted to slide either above or below said projection as the drawer is reciprocated; a pivoted inclined plane or switch point at the forward end of said rib normally yieldingly held in position to move the projection to cause the lever to move the aforesaid rod to a position to engage the fare box cover as the drawer is drawn outward, the rib being so proportioned that when the drawer is fully drawn out the projection is free to pass to the other side of the rib and to lift and pass the switch point as the drawer is pushed in again; and a rearward extension of the front of the drawer adjacent to the rod and lever adapted to maintain the closure of the opening in the casing until said rod has been moved towards the closing position.

13. A fare box having a binged cover and provided with a pivoted dog at one side normally engaging the cover to hold it slightly raised in combination with fare collecting apparatus having an opening to receive the box and provided with a part adapted to rock the dog to disengage it from the lid as the box is inserted through said opening and to maintain it in the disengaged position while the box is within the apparatus.

Dated at Toronto in the Province of Ontario, Canada this 1st day of June, A. D. 1908.

JOSEPH H. COLEMAN.

In the presence of—

E. MERNER,
D. S. TOVELL
